UNITED STATES PATENT OFFICE.

JOHN W. CROUSE, OF RATON, NEW MEXICO.

RAILWAY-TIE.

1,048,948.

Specification of Letters Patent. Patented Dec. 31, 1912.

Application filed July 31, 1912. Serial No. 712,528.

To all whom it may concern:

Be it known that I, JOHN W. CROUSE, a citizen of the United States, residing at Raton, in the county of Colfax, State of New Mexico, have invented certain new and useful Improvements in Railway-Ties; and I do hereby declare the following to be a full, clear, and exact description of the invention, such as will enable others skilled in the art to which it appertains to make and use the same.

This invention relates to combined steel and reinforced concrete railway ties and has for an object to provide a tie of this character in two pieces hingedly connected together by a double hinge and each carrying means for safely securing a rail.

A further object of the invention is to provide a novel hinge including members adapted to be embedded axially in the cement blocks, a pair of connecting links being arranged on opposite sides of the exposed ends of the members, and two pintles being passed through the links and exposed ends of the embedded member to produce a double hinge capable of permitting movement of either block relatively to the other without disturbing the said other block.

With the above objects in view the invention consists of certain novel details of construction and combination of parts herein-after fully described and claimed, it being understood that various modifications may be made in the minor details of construction within the scope of the appended claims.

In the accompanying drawings forming part of this specification:—Figure 1 is a plan view of the tie. Fig. 2 is a longitudinal sectional view taken on the line 2—2. Fig. 1. Fig. 3 is a cross sectional view taken on the line 3—3 Fig. 1. Fig. 4 is a detail perspective view of one member of the hinge showing the means for anchoring the same in the cement block. Fig. 5 is a side elevation of the metal parts of the tie. Fig. 6 is a cross sectional view taken on the line 6—6 Fig. 5. Fig. 7 is a detail perspective view of one of the rail securing means. Fig. 8 is a detail perspective view of one of the I beams.

Referring now to the drawings in which like characters of reference designate similar parts, 10 designates traffic rails and 11 designates concrete blocks which support the rails and coöperate in forming a single railway tie.

By referring especially to Figs. 2 and 3, it will be seen that both blocks are connected by a hinge comprising a pair of channel iron members 12 each of which is embedded axially in its related block and is provided with anchoring devices 13 of the general type shown in Fig. 4, such anchoring devices each comprising a single oblong loop of stiff rod material the sides of which are passed through openings 14 in the flanges of the channel iron members and then bent downwardly therefrom as clearly shown in Fig. 3. One end of each of the members 12 is exposed beyond the inner end face of the related block and is equipped with a hinge eye 15. A pair of links 16 is arranged on opposite sides of the hinge eyes 15, and a pindle 17 is passed through each hinge eye and the adjacent ends of the links.

By means of the employment of two links and two pintles, either block may move vertically relatively to the mating block of the tie without appreciable displacement of the said mating block, and furthermore by the employment of the anchoring devices 13 rigidly securing each channel iron member 12 in its related block, movement of the blocks toward or away from each other is positively prevented and thus the traffic rails are maintained at the proper gage at all times.

In the manufacture of the concrete blocks, a plurality of twist bars 18 are embedded longitudinally in the block to reinforce the block to resist torsional and other stresses. Each channel iron member is equipped with an I beam 19 the base flange of which is bolted as shown at 20 or otherwise secured to the web of the channel iron member. The head flange of the I beam is provided with a transverse dove-tail slot 21 to receive the traffic rail, the walls of the slot forming shoulders which bear snugly against the edges of the rail base flange and prevent spreading of the rail as will be understood.

A rail clamp 22 is bolted or otherwise secured to the head flange of the I beam as shown at 23 and engages over the base flange of the inner side of the rail, and a second rail clamp 24 is arranged on the head flange of the I beam and engages with the outer side of the rail, this clamp being bolted as shown at 25 or otherwise secured to the head flange of the beam.

What is claimed, is:—

1. A railway tie including spaced concrete blocks, and a hinge connecting said blocks

including a channel iron member embedded in each block and having a terminal hinge eye exposed beyond the inner face of the block, spaced links arranged on opposite sides of said hinge eyes, and a pintle passed through each hinge eye and the adjacent ends of said links.

2. A railway tie including spaced concrete blocks, a channel iron embedded in each block and having a terminal hinge eye exposed beyond the inner end face of the block, spaced links on opposite sides of said hinge eyes, a pintle passed through each hinge eye

and through the adjacent ends of said link, and a plurality of anchoring devices embedded in each slot, each comprising a loop of stiff rod material having the sides passed through the flanges of the related channel iron and thence bent downwardly therefrom. 15

In testimony whereof, I affix my signature, in presence of two witnesses. 20

JOHN W. CROUSE.
